UNITED STATES PATENT OFFICE.

GUILLAUME C. LAURENCY AND MARCEL VIGIER, OF LONDON, ENGLAND.

CARDING MACHINE.

Application filed May 26, 1921. Serial No. 472,850.

(GRANTED UNDER THE PROVISIONS OF THE ACT OF MARCH 3, 1921, 41 STAT. L., 1313.)

To all whom it may concern:

Be it known that we, GUILLAUME CLEMENT LAURENCY, a subject of the King of Belgium, and MARCEL VIGIER, a French citizen, both residents of London, in the county of London, England, have invented certain improvements in Carding Machines (for which we have applied for a patent in Great Britain, on November 21, 1919, Patent Number 29011), of which the following is a specification.

This invention relates to the main carding cylinders and doffing cylinders of carding machines; and it consists in the novel construction and combination of the parts hereinafter fully described and claimed.

In the drawings, Figure I is a side view of portions of a main carding cylinder, and a doffer constructed according to this invention, portions of the doffer being shown broken away. Fig. II is an end view of the doffer, partially in section.

The direction of rotation of the main card cylinder A of the machine and that of the improved doffing cylinder B are indicated by the arrows 1 and 2, and 2^a designate the needles or card teeth of the doffing cylinder, having their points directed forwardly or in the direction of rotation.

Metallic wires 3 stretched between sectors 4, which are arranged in the form of a crown at each end of the doffing cylinder B, participate in the movement of the latter about its axis, but describe an eccentric path with regard to said axis. This eccentricity is determined by a fixed cam 5, on which a disc 6 can turn freely, by means of bars 8, which carry sectors 4 to which the metallic wires 3 are fixed and which slide at an angle of 25 degrees into notches formed for that purpose in the cheeks of the cylinder. The bars are carried by the disk 6 and follow the radius of the edge 7 of said disc, the axis of which is displaced by the cam 5. Following the movement of said edge 7, the bars 8 and consequently the sectors 4 with the metallic wires, are moved away from or approached to the axis of the cylinder, according as the revolutions of the latter remove them from or bring them nearer to the main card cylinder A, and the wires 3 are thus hidden at the foot of the needles of the doffing cylinder while it is being loaded with fibres, (see left-hand part of Fig. 1) and move outwards

from said needles on being removed from the main card cylinder. The fibres are thus raised or moved by the wires above or beyond the needles 2^a and are thus completely liberated from the latter, as shown at the right-hand part of Fig. 1.

A ring 9 serves as a guide for the lower ends of the sliding bars 8, while keeping them all the time in the notches. The cam 5 can be fixed in different positions and may be advanced by about one quarter of a revolution when it is desired to grind the cylinder fittings 2^a so that the metallic wires 3 may be at the bottom of the needles when they are acted upon by the grinding means. A knife 11 located between the cylinders A and B can be regulated with regard to the carding point, to vary the intensity of the cleaning and carding of the fibres by the needles of the main card cylinder.

It is well known that it is not possible to increase the peripheral speed of the doffer with regard to that of the main card cylinder, in order to increase the production of present-day carding machines, all increase of speed diminishing the capacity for transmitting the fibres between these two parts of the machine, and in consequence diminishing the production of the machine. This defect, which prevents any improvement, not only in the production but also in the quality of the work produced, does not exist with the present invention. The direction of rotation of the doffing cylinder, indicated in Fig. 1, dispenses with the necessity for having a fixed speed of said doffing cylinder with regard to that of the main card cylinder, and owing to this novel method of working, all increases of speed of the doffing cylinder increase the capacity for transmitting fibres and consequently increase the production of the machine.

If the doffer of the carding machine revolves with a peripheral speed equal to the peripheral speed of the main card cylinder, its needles will not take the fibres when they pass near said cylinder, and no fibres will be delivered from the machine, but if its revolutions are effected in the opposite direction as described above, all the needles will become loaded with fibres. The speed of the doffer must consequently be reduced as much as possible, but this lower speed must be sufficient for the discharge of the fibres

which it has collected. That is the fixed condition which is imposed for the doffers of all carding machines of the present day. In these conditions, if the speed of the doffer 5 is reduced to 50 revolutions for the necessary time for producing say, 5 lbs. of cotton for example, the output of our improved carding doffer, with the same reduction to 50 revolutions and for the same time of working 10 will be of 5 lbs. + 5 lbs. = 10 lbs.: and in doubling the speed this production will be 20 lbs., whereas in doubling the speed of the doffer of the present day carding machines, the production will be something like zero, 15 seeing that the doffer has the peripheral speed of the main cylinder.

The direction of rotation of the doffing cylinder B as described, allows the needles of the main card cylinder A to clean, separate and parallelise the fibres which it attaches to the needles of the doffer cylinder, and as these fibres are liberated from the latter without disturbing the parallelism which has been given to them in the carding machine, the devices hereinafter described, the object of which is to preserve and increase the parallelism in the subsequent operations will finally produce laps or slivers, with parallelised fibres.

Such action of the doffing cylinder B is distinct from a known device in carding machines in which there is used a transferring cylinder having the points of its teeth in the direction of its rotation but which only reverses the fibres without carding or combining them.

For the preparation of fibres for the spinning of waste, carded wool, etc., the fibres usually pass through three carding machines, the first two rolling the sheet or web of fibres into a lap, which the last forms again into a web. The latter is afterwards divided into narrow ribbons which form the slubbings for the drawing frames or spinning mules.

A device for forming laps of fibers is arranged on the opposite side of the doffer B from the carding cylinder A. A portion of this device is shown in Fig. I, and it has

an endless apron which passes over rollers 50 12 and 14.

What we claim is:

1. The combination, with a carding cylinder, of a doffer adapted to be revolved in the reverse direction from the carding cylinder, said doffer comprising a cylinder provided with card teeth at its periphery and having guide notches in its ends, stationary cams arranged at the ends of the doffer cylinder, disks revoluble with the doffer cylinder on the cams and moving towards and away from the carding cylinder as the doffer is revolved, bars connected to the disks at one end and slid able in the said notches, and wires supported between the free end portions of the said bars and extending longitudinally of the doffer cylinder and movable into and out of engagement with its card teeth.

2. The combination, with a carding cylinder, of a doffer adapted to be revolved in the reverse direction from the carding cylinder, said doffer comprising a cylinder provided with card teeth at its periphery and having guide notches in its ends, stationary cams arranged at the ends of the doffer cylinder, disks revoluble with the doffer cylinder on the cams and moving towards and away from the carding cylinder as the doffer is revolved, bars connected to the disks at one end and slid able in the said notches and arranged with their free outer ends in advance of their inner ends in the direction of the revolution of the doffer cylinder, sectors secured to the free ends of said bars, and wires extending longitudinally of the doffer cylinder between the said sectors and movable into and out of engagement with its card teeth.

In testimony whereof we have hereunto 90 set our hands in the presence of two witnesses.

G. C. LAURENCY.
M. VIGIER.
